UNITED STATES PATENT OFFICE.

HANS ERNST, OF MÜNSTER, GERMANY.

INDICATOR FOR SAUSAGE-STUFFING MACHINES.

No. 827,147.

Specification of Letters Patent.

Patented July 31, 1906.

Application filed May 25, 1904. Serial No. 209,744.

To all whom it may concern:

Be it known that I, HANS ERNST, a subject of the King of Prussia, German Emperor, residing at Münster, in the Province of Westphalia, Kingdom of Prussia, and German Empire, have invented certain new and useful Improvements in Indicators for Sausage-Stuffing Machines, of which the following is a specification.

10 The present invention relates to apparatus for fitting to machines for filling or stuffing sausages, the purpose of which is to indicate when a definite predetermined quantity of mince-meat or the like has been filled into the intestine, so that sausages turned out by the machine may all be of exactly the same weight.

One form of construction of the new apparatus is shown in the accompanying drawings, in which—

Figure 1 is a side elevation of the device applied to a sausage-stuffing machine with vertical cylinder. Fig. 2 is a side elevation of the indicating device alone, drawn to an enlarged scale. Fig. 3 is a front elevation of the same seen in the direction of the arrow, Fig. 2. Fig. 4 is a section taken on the line A B of Fig. 1 and shows a detail to be herein-after referred to.

30 The new device can be fitted to any ordinary sausage-stuffer provided that means are furnished for transmitting to the device the motion of the piston employed for forcing the meat into the gut and for enabling fitting of the adjustment device for the determination of the weight.

The improved apparatus is, by way of example, shown in the drawings as being fitted to a sausage-stuffing machine with upright cylinder.

40 The mince-meat cylinder of the machine contains a piston *b*, having a screw-spindle *a*. The piston is worked by means of the friction-disk *c*, provided with an internally-threaded sleeve or boss, which actuates the screw-spindle *a*, which disk *c* again is driven by means of the friction-roller *d* of a shaft driven by hand or by belt-pulley. The shaft is mounted in the frame of the machine and 45 in the collar *d'* and can be continuously driven. This shaft imparts motion to the disk *c* by means of the friction-roller *d*, which is pressed against the friction-disk *c* by the friction-disk *e*. To this purpose a link *t* is 50 pivoted to the hub of said disk *e*, the other

end of said link being pivoted to the arm *u* of a lever *v*, fulcrumed on the frame of the machine in such a manner that upon depressing the said lever *v* the disk *e* is raised by means of the link *t* to such an extent that it will press 60 the roller *d* against the friction-disk *c*. This also causes the friction-roller *g*, carried by the shaft *f*, which is mounted in the same manner as the shaft of the roller *d*, to come in contact with the disk *c*. The roller *g* will thus be 65 set in rotation, which motion will be transmitted to the pinion *h*, keyed to the end of the shaft *f*, which projects beyond the framing. The pinion *h* is designed to mesh at 70 intervals with the toothed wheel *i*, mounted on the frame of the machine. The wheel *i* may be suitably balanced by means of a counterweight or the like, so that on being released from the pinion *h* it always returns automatically to its position of rest, Fig. 3. In the 75 particular construction shown in the drawings the toothed wheel *i* is for this purpose shown as being cast with a web of metal between two of the spokes. To this wheel *i* one end of a spring-arm *k* is secured, at the 80 other end of which a roller *l* and a clapper *m* are provided.

Between the wheel *i* and the frame of the machine a stationary segmental plate *n* is arranged having a curved inclined track *o*, running in the manner of a screw-thread relatively to the shaft of the wheel *i*. A gong *p* is also provided on the segment *n*. For a purpose to be described the track *o* at the gong *p* rises somewhat above the level of the 85 segment *n*, while the other end lies at the same level as the latter. The part which holds the track *o* and the gong *p* is secured by means of a thumb-nut *q*, which works in a slot *r*, so as to admit of adjustment of the 90 parts.

The friction-roller *g* slides on the shaft *f*, which is provided with groove and feather for the purpose. The forked end of a rod *s*, Figs. 1 and 4, engages in an annular groove in 100 the roller *g*, whereby the position of the roller on the shaft *f* can be adjusted.

The operation of the apparatus is as follows: By raising the disk *e* the friction-disk *c* and the roller *g* are set in rotation, and at the 105 same time the pinion *h*, being mounted on the shaft *f*, engages with the wheel *i* and rotates in the direction of the arrow, Fig. 3. The wheel *i* will thus also be rotated and the roller *l* caused to run on the track *o*, and since 110

the arm *k* is of resilient material the roller *l* is able to ascend the said track. When the roller *l* has thus reached the end of the track *o*, it will, owing to the resilience of the arm *k*, suddenly snap down, and the clapper *m* will strike the gong *p*, thus giving an audible signal. The device for feeding the mince-meat into the gut can now be brought out of operation and the filled gut closed. On stoppage of the filling device the wheel *i* will return, as already described, to its initial position, the roller *l* running freely below the first part of the track *o*, (which near the gong *p* is elevated,) and then forcing its way along beneath the rest of the track, which being of resilient material allows it to pass. Thus the ringing of the bell signals that a definite quantity of mince-meat has been fed into the intestine from the supply-cylinder. Owing to the roller *g* being capable of adjustment on the shaft *f* by the aid of the rod *s* a larger or smaller quantity of mince-meat can be fed from the cylinder into the gut, depending upon the weight required. Since the exact moment when the bell rings depends upon the speed of rotation of the pinion *h*—that is to say, of the friction-roller *g*—and since the speed of rotation of the latter again depends upon its distance from the center of the disk *c*, it is obvious that this disk will only execute a larger or smaller part of a rotation before the bell rings. If the roller *g* is located quite near the center of the disk *c*, the latter will make almost a complete rotation before the bell rings. If, on the contrary, the roller *g* is located near the periphery of the disk *c* the bell will ring when the disk *c* has made only about one-sixth to one-seventh of a rotation. Since, however, it is upon the extent of rotation of the disk *c* that the quantity of mince-meat fed into the gut is dependent, it is obvious that the weight of each sausage can in this manner be accurately determined. The requisite position of the roller *g* for any desired weight of mince-meat can be readily ascertained by experiment, and the rod can in this manner be marked with a scale of weights. The volume of a given weight of mince-meat naturally depends upon the percentage of fat and the fineness to which the meat has been chopped, &c., so that the time required by the piston to feed a given weight of meat into the gut will vary. For the purpose of compensating for this the inclined track *o* is made adjustable, and a scale is also provided on the segment, the divisions of which corre-

spond to the various different kinds of sausage.

The arrangement of a piston having a screw-threaded rod on which two disks are revolvably mounted, one of which is constructed to engage the thread on the rod, and an adjustable roller between the disks adapted to contact with them, as described herein, has been claimed in my application, Serial No. 209,743, filed May 25, 1904.

What I claim as my invention, and desire to secure by Letters Patent, is—

1. In a sausage-stuffing machine, the combination with a frame, a main driving-shaft and an intermediate shaft mounted therein, in the same plane, and frictional driving mechanism between the two shafts, including a roller longitudinally adjustable along said intermediate shaft, of a rotary body mounted on said frame and having a spring-arm, a gong on the frame, and means for throwing the intermediate shaft into and out of gear with the rotary body. 75

2. In a sausage-stuffing machine, the combination with a frame, a main driving-shaft and an intermediate shaft mounted therein, in the same plane, and frictional driving mechanism between the two shafts, including a roller longitudinally adjustable along said intermediate shaft, of a rotary body mounted on said frame and having a spring-arm, a gong on the frame, means for throwing the intermediate shaft into and out of gear with the rotary body, and an inclined track for the said spring-arm to travel along. 80

3. In a sausage-stuffing machine, the combination with a frame, a main driving-shaft and an intermediate shaft mounted therein, in the same plane, and frictional driving mechanism between the two shafts, including a roller longitudinally adjustable along said intermediate shaft, of a rotary body mounted on said frame and having a spring-arm, a gong on the frame, means for throwing the intermediate shaft into and out of gear with the rotary body and an inclined track for the said spring-arm to travel along, both the gong and the track being adjustable on a supporting-bracket. 90

In testimony whereof I have signed my name to this specification in the presence of two subscribing witnesses.

HANS ERNST.
